N-PHENYL-2-SUBSTITUTED PHENYLAMINO-1,4-NAPHTHOQUINONEIMINE COMPOUNDS AND METHODS OF PREPARING THE SAME

Robert G. Shepherd and Jackson P. English,
Stamford, Conn., assignors to American Cyan-
amid Company, New York, N. Y., a corporation
of Maine

No Drawing. Application March 27, 1951,
Serial No. 217,882

6 Claims. (Cl. 260—396)

1

This invention relates to new N-phenyl-2-(substituted phenylamino)-1,4-naphthoquinoneimines, their addition salts with acids and methods of preparing the same. The new compounds of this invention, when in the form of their free bases, may be represented by the following structural formula:

in which R represents a lower dialkylamino substituent. The new naphthoquinoneimines may be isolated in the form of their free bases and as such are crystalline compounds soluble in most common organic solvents. Of course, the new compounds may also be prepared in the form of their acid addition salts, for instance as the hydrochloride, nitrate, or citrate. When in the form of their free bases, the new compounds are red-violet dyes and in the form of their acid addition salts they are green-blue dyes.

The new compounds of this invention, whether in the form of their free bases or in the form of their acid addition salts, show high activity against tubercle bacilli. While the exact nature of the activity is not fully understood, it is known that the activity is greatly influenced by the variation of the group represented by R in the above structural formula. This substituent must be a lower dialkylamino group, for instance dimethylamino, methylethylamino and diethylamino. If R in the above formula represents hydrogen or a substituent such as ethoxy and phenylamino, the compounds are much less active, if not completely so.

The following table is for the purpose of showing the critical nature of the substituent labeled R in the above structural formula. The table represents the results of tests in which mice infected with a virulent strain of tubercle bacilli were fed, beginning on the day of infection, a selected naphthoquinoneimine mixed with their food in an amount equal to 0.4% by weight of the food for a period of fourteen days after which treatment was discontinued. The median survival time of the mice so treated was calculated and is as given in the table. The virulence of the infection was such that the untreated controls had a median survival time of fourteen days.

2

	R	Median Survival Time
5	$\text{NC}_2\text{H}_5)_2$	24 days.
	H	Less than 18 days. ¹
	OC_2H_5	Do. ¹
	NHC_2H_5	Do. ¹
	Controls	14 days.

10 ¹ As an increase of three days or less in median survival time is small enough that it might conceivably be attributed to other factors, compounds showing no more than this were simply marked "Inactive" in test reports.

It should not be inferred from the above tests that the naphthoquinoneimines are only effective in the amounts there employed. In fact, more beneficial results are usually obtained if the new compounds are employed in increased amounts. It should likewise not be inferred that treatment should be discontinued after a certain period of time as was done in the tests. No toxic effects of the new compounds have been observed and they may be employed for as long a period as desired.

The new compounds of the present invention offer advantages over the antibiotics now commonly employed against tubercle bacilli infections in that they are orally administered. Also, there has been no tendency observed for the new compounds to cause the development of drug resistant strains.

While it is intended that this invention cover the new compounds regardless of how they are prepared, a particularly convenient method of preparing the new compounds has been discovered and this method also constitutes a part of this invention. The new method comprises reacting a 4-anilino-1,2-naphthoquinone with the appropriately substituted aniline compound as illustrated by the following equation:

3

The reaction is preferably performed in an organic solvent such as illustrated by the following: aliphatic alcohols, for instance ethanol or butanol; and cyclic ethers, for instance dioxane. The reaction may be performed within a wide range of temperatures, for instance 60° to 130° C., with the preferred range being 100° to 120° C. The reactants should be heated together for at least one hour and in some cases as long as twenty-four hours if high yields are desired.

The invention will be more particularly illustrated by means of the following examples in which all parts are by weight unless otherwise indicated.

EXAMPLE

N-phenyl-2-(p-diethylaminophenylamino)-1,4-naphthoquinoneimine

Seven and one-half parts of 4-anilino-1,2-naphthoquinone and 6 parts of p-diethylaminoaniline hydrochloride are added to 3 parts of triethylamine and 100 parts by volume of n-butanol. The mixture is heated under reflux for two hours, cooled, and the separated solid filtered. This material is crystallized from a large volume of heptane to give purified N-phenyl-2-(p-diethylaminophenylamino)-1,4-naphthoquinoneimine.

Other naphthoquinoneimines of this invention are prepared by substantially the same procedure. For instance, in place of the p-diethylaminoaniline hydrochloride in the above example, one can substitute equal molar quantities of p-dimethylaminoaniline hydrochloride or p-dipropylaminoaniline hydrochloride to produce N-phenyl-2-(p-dimethylaminophenylamino)-1,4-naphthoquinoneimine and N-phenyl-2-(p-dipropylaminophenylamino)-1,4-naphthoquinoneimine respectively.

We claim:

1. Compounds represented by the formula

10

15

4

2. N-phenyl-2-(p-diethylaminophenylamino)-1,4-naphthoquinoneimine.

3. N-phenyl-2-(p-dimethylaminophenylamino)-1,4-naphthoquinoneimine.

4. N-phenyl-2-(p-dipropylaminophenylamino)-1,4-naphthoquinoneimine.

5. A method of making compounds represented by the formula

20

in which R₁ and R₂ represent lower alkyl radicals which comprises reacting at a temperature of 60-130° C. 4-anilino-1,2-naphthoquinone with a compound represented by the formula

in which R₁ and R₂ represent lower alkyl groups.

6. A method of making N-phenyl-2-(p-diethylaminophenylamino)-1,4-naphthoquinoneimine which comprises reacting at a temperature of 100° C. to 120° C. 4-anilino-1,2-naphthoquinone with p-diethylaminoaniline.
